Patented May 21, 1912.

UNITED STATES PATENT OFFICE.

ERWIN C. SHERMAN, OF YOUNGSTOWN, OHIO, ASSIGNOR TO THE WILLIAM B. POLLOCK COMPANY, OF YOUNGSTOWN, OHIO, A CORPORATION OF OHIO.

LADLE-CAR.

1,026,708.

Specification of Letters Patent.

Patented May 21, 1912.

Application filed April 29, 1911. Serial No. 624,191.

To all whom it may concern:

Be it known that I, ERWIN C. SHERMAN, of Youngstown, Mahoning county, Ohio, have invented a new and useful Improvement in Ladle-Cars, of which the following is a full, clear, and exact description, reference being had to the accompanying drawings, forming part of this specification, in which—

10 Figure 1 is an end view of a ladle car embodying my invention; Fig. 2 is a similar view, largely diagrammatic, illustrating the dumping movement of the ladle; and Fig. 15 3 is a sectional plan view showing a modified construction.

My invention has relation to dumping or ladle cars of that type in which the ladle is emptied by pouring from a spout located at or near the top of the ladle. In cars of 20 this character as ordinarily constructed heretofore, when the ladle is tipped in the frame of the car there is considerable drop to the spout while pouring; and in order to bring the final position of the spout in 25 the proper relation to the receptacle poured into, it has been necessary either to allow considerable fall to the metal during the first part of the pouring, which has resulted in great loss due to the splashing of 30 the metal, or to lift the ladle from the car by means of an overhead crane and place it in a tilting cradle so arranged as to give a shorter fall of the metal, or to provide a movable trough which moves with the spout 35 on the ladle. These expedients cause considerable inconvenience and added expense in the handling of the metal.

The present invention is designed to provide means whereby a novel tipping action 40 of the ladle is obtained, resulting in a large decrease in the drop of the spout during the pouring operation.

In the accompanying drawings, the numeral 2 designates any usual or suitable 45 truck of a ladle car, and 3 the frame of the car supported on the truck.

4 is the ladle, and 5 indicates a receptacle, into which the contents of the ladle are to be poured. The ladle is provided at each 50 end with a supporting projection 6, these projections normally resting upon the supporting surfaces 7 on the end frames of the car. The ladle is provided near its top and at opposite sides of its center with the projecting trunnions 8, which rest in the open 55

bearings 9 formed in the upper ends of the upwardly projecting portions 3^a of the car end frames. In dumping, the ladle is tilted upon one or the other of the trunnions 8, according to whether it is desired to pour 60 to the right or to the left, and as these trunnions are located high up on the car, it will be apparent that the movement of the ladle spout 10 during the pouring operation will be very largely reduced. 65

In Fig. 1 I have shown the trunnions 8 as being carried by separate castings, which are secured to the ladle. In the modification shown in Fig. 3, I have shown the supporting projections 6, which carry the usual 70 ladle trunnions 6^a, as having integral extensions 6^b, upon which the trunnions 8^a (corresponding to the trunnions 8) are formed. The two extensions 6^b are connected by tie rod 6^c and a spacer or separator 6^d is placed upon the tie rod between 75 said extensions. This construction provides a square supporting frame around the top of the ladle, which tends to prevent the top of the ladle from buckling and keeps the 80 trunnions 8^a centered so that they are always alined with the open bearings.

Owing to the high center of movement of the ladle, it is obvious that there will be a considerable tendency of the entire car to 85 tip during the pouring operation owing to the shifting to the center of gravity. To overcome this tendency, I preferably provide the lower portion of the frame of the car with the supporting feet or projections 90 11, which are adapted to rest upon the supports 12 adjacent to the track 13 upon which the car travels. I also preferably provide, adjacent to the supports 12 a suitable hook 14, which will engage over the 95 projection 11 at the side of the car opposite to that at which the pouring takes place and which serves to hold down the frame of the car and to prevent the car from tipping. The hook, however, may be used without the 100 supports, or the supports without the hook, or any other suitable means may be employed for preventing the car from tipping during the pouring operation. The trunnions 8 are so located that their centers are 105 in vertical lines which fall outside of the track rails 13.

What I claim is:—

1. A ladle car having a tipping ladle supported thereon, the ladle having a bearing 110

member whose center lies in a vertical line outside of the track upon which the car stands, and the frame having a bearing for said bearing member, together with means for preventing tipping of the car during the tipping movement of the ladle; substantially as described.

2. A ladle car having upwardly projecting end frames extending above the center of the ladle, and a ladle supported on said car and having bearing members provided with open bearings on the upwardly projecting end frames, the centers of said bearing members being outside of the rail upon which the car stands, and means for engaging the car to prevent tipping thereof during the dumping movement of the ladle; substantially as described.

3. The combination with a ladle car having a pivoted ladle adapted to tip on a center which is outside of the track upon

which the car stands, of means adjacent to said track for engaging the frame of the car to prevent the tipping thereof during the dumping movements of the ladle; substantially as described.

4. A ladle car having a frame provided at each end with upwardly extending portions formed with open seats at their upper ends, and a ladle having supporting members secured to opposite sides thereof, said supporting members having arms or extensions provided with trunnions or bearings adapted to engage said open seats, together with tie means connecting each pair of said extensions; substantially as described.

In testimony whereof, I have hereunto set my hand.

ERWIN C. SHERMAN.
